LEG SUPPORTING CUSHION FOR A PROFESSIONAL CHAIR OR A SIMILAR ARTICLE

William T. Scholl, Sr., Vanderburgh County, Ind.

Application January 23, 1959, Serial No. 54,284

Term of patent 14 years

(Cl. D15—3)

Fig. 1 is a perspective view of a leg supporting cushion for a professional chair or similar article, showing my design;

Fig. 2 is a view in side elevation of the instant leg supporting cushion, apart from any other structure; and

Fig. 3 is a view in front elevation of the leg supporting cushion of Fig. 2.

The dotted lines are for illustrative purposes only.

I claim:

The ornamental design for a leg supporting cushion for a professional chair or a similar article, as shown and described.
